UNITED STATES PATENT OFFICE.

GUSTAVE SCHUBACH, OF HOLYOKE, MASSACHUSETTS, ASSIGNOR TO WHITE & WYCKOFF MANUFACTURING COMPANY, OF HOLYOKE, MASSACHUSETTS, A CORPORATION OF MASSACHUSETTS.

STACKING MECHANISM.

Application filed October 6, 1920. Serial No. 415,190.

To all whom it may concern:

Be it known that I, GUSTAVE SCHUBACH, a citizen of the United States, residing at Holyoke, in the county of Hampden and State of Massachusetts, have invented new and useful Improvements in Stacking Mechanisms, of which the specification was filed on October 6, 1920, under Serial No. 415,190.

10 This invention relates to improvements in stacking mechanisms, and more particularly to the segregating and controlling devices therefor.

15 This device is adapted for general application where it is desired to count out and segregate articles into stacks or groups each of which contains a particular predetermined number of articles, but is particularly applicable for use in connection with 20 an envelope making machine.

With an envelope making machine it is commonly desired to segregate the envelopes being delivered by the machine into stacks containing a certain number of envelopes for the purpose of banding or packing the said stacks.

25 It is important that the envelopes be accurately counted with respect to each stack in order that the banded or packed stacks of envelopes shall contain a definitely known or predetermined number.

30 My stacking mechanism to be hereinafter more fully described is adapted and arranged to be operated in unison with an envelope or other machine and is provided with means to accurately count only such envelopes as are actually delivered thereto. Means operable by the counting means when the counting has been completed are also 35 provided, to displace or mark off an envelope as it is delivered to the device whereby a stack of envelopes is segregated in such a manner that the said stack is easily distinguished from other stacks and facilitates its removal from the said stacking 40 device.

45 One object of the invention is to provide a device that is adjustably adapted to segregate articles into stacks containing various predetermined numbers of articles.

50 Another object is to provide a device having detecting means which controls the

counting means, thereby facilitating the accurate counting of articles in each segregated stack.

55 Another object is to provide a stacking mechanism that is automatic in its operation in that means are provided whereby the counting operation is recommenced after each segregating movement of the displacing or marking-off device.

60 Other objects and advantages will appear in the following description in which will be pointed out such novel features of construction and combination of parts as shall 65 be more fully described and pointed out in the appended claims.

65 The embodiment of my invention as at present preferred is described in the following description and illustrated in the accompanying drawings in which:

70 Fig. 1 is a side elevational view;

Fig. 2 is a sectional view on the line 2—2 of Fig. 1;

Fig. 3 is a sectional view on the line 3—3 75 of Fig. 1;

Fig. 4 is a fragmentary view of the displacing shaft; and

Fig. 5 is a fragmentary view of the operating slide therefor.

80 1 represents the U-shaped trough or chute usually located at the delivery end of an envelope-making machine and which for illustrative purposes consists of the side walls 2 and 3 and the lower bottom wall 4. 85 A plunger 5 represents the usual reciprocating delivery plunger of an envelope machine which usually is operated intermittently to successively deliver the completed envelopes to the said chute 1.

90 A connecting rod 6 for operating the counting and displacing mechanism hereinafter described may be connected to and operated by the same envelope machine in unison with the delivery plunger for the 95 purposes as will hereinafter appear.

95 A curved bottom plate 7 having a depending extension 7' is carried by the bottom side 4 of the chute and is provided with bearing lugs 8 in which lugs is rotatably mounted a 100 shaft 11.

For the purpose of controlling the operation of the counting and displacing mechanism detectors 10 are provided which

comprise curved envelope engaging arms or feelers fixed to the shaft 11 and rods 12 projecting therefrom on which counter-balances 12' are adjustably carried to maintain the detectors in their normal raised position shown in Fig. 1. Slots 9 arranged in a spaced relation are provided in the plate 7 for the reception of the detectors 10.

The detectors are adapted to engage on 10 their upper curved sides the envelopes as they are delivered to the chute by the plunger 5 as best shown in Fig. 1. The counter-balances 12' are preferably so adjusted with respect to the weight of an envelope, that 15 the detectors are easily depressed by an envelope during its passage thereover, and the slots 9 of the plate 7 allow the detectors to lie therein in order that the bottom edge of the envelope may slide from off the detectors 20 onto the plate 7.

While two detectors are shown in the embodiment of the invention at present preferred it is obvious that the device would be operative if one or several such detectors 25 should be used.

A projecting contact member 13 fixed to the shaft 11 and located intermediate the detectors 10 normally abuts an insulation block 14 which is fixed to the depending plate 7' 30 and serves as a stop to prevent an upward movement of the detectors from their normal raised position shown in Fig. 1.

A contact 15 carried by the insulating block 14 is so disposed with reference to the 35 contact member 13, that when the detector is depressed and the shaft 11 rotated by an envelope being deposited thereon, a contact is made between the contact members 13 and 15 to close an electro-magnetic circuit for 40 the purpose which will be hereinafter more fully described. While such contacting devices are shown as are capable of closing the magnetic circuit, it is obvious that other devices operable by the movement of the 45 detector may be employed.

Depending lugs 16 are carried by the plate 7 and carried pivotally mounted therein a shaft 17 to either end of which is fixed counterweighted triggers 18. These triggers 50 are adapted to be depressed by an envelope being slid over their upper sides and are returned to their normal position shown in Fig. 1 by their counterweighted portions 18'. Stops 19 secured to the underside of 55 plate 7 are so disposed as to prevent the triggers from raising above their normal raised position shown in Fig. 7. These triggers are adapted to engage the lower edge 60 of an envelope fed there-past and hold the same in an upright position against the stack of envelopes in the chute in the manner best shown in Fig. 1.

Other devices (not shown) such as a yieldable plate or the like may be provided in the chute 1 against which the envelopes are 65

pressed when delivered over the detectors and past the trigger, the function of which is to hold the envelopes in a compact pile. Thus, an envelope delivered by the pusher, depresses the detectors and closes the circuit 70 controlling the counting mechanism and is finally held against the stack by the triggers.

The means for segregating the envelopes into stacks of a predetermined number comprises in the present embodiment of the invention, a counting mechanism for counting each envelope as it is delivered to the chute and a displacing mechanism operating to transversely displace the rear-most envelope 80 of each stack so as to mark off the separate stacks.

The counting mechanism comprises a counter 20 which is preferably in the form of a wheel sector having teeth or notches 21 85 in its periphery and pivotally mounted upon a stud 22 carried by the side wall 3 of the chute. A pivoted actuated pawl 23 carried on a reciprocating slide 30' is adapted to engage the notches of the sector 20 to rotate 90 the same clockwise in a step-by-step manner for the counting operation. A radial arm 22' fixed to the said sector 20 is adapted to engage and actuate the displacing or marking-off mechanism as will be hereinafter 95 described.

A retaining pawl 25 pivotally mounted upon the side wall 3 of the chute is adapted to engage the notches 21 of the counting sector to check the said sector against a 100 counterclockwise rotation after each clockwise counting step. This pawl 25 is further provided with an extension 25' which is adapted to be engaged by locking devices which hold the said pawl from engagement 105 with the notches of the counting sector while the same is returning to its initial position after each counting operation. A tension spring 65' attached to the said pawl 25 and to the wall 3 of the chute functions to hold 110 the pawl in engagement with the counting sector notches during the counting operation.

A peripheral cam surface 24 is provided on the sector 20 adjacent the notches 21 thereof and is disposed eccentrically of the pivotal axis of said sector and fuctions to move from the notches 21, the retaining pawl 25 after the counting operation has been completed. Suitable characters as indicated are provided on the sector 20 adjacent the notches for the purpose later to be described.

A tension spring 26 secured to the wall 3 of the chute and sector 20 by suitable studs or the like is adapted to rotate 125 the said sector in a counterclockwise direction when the retaining pawl 25 has been moved by the cam 24 from engagement with the notches 21 at the completion of the counting operation.

An adjusting arm 27 is pivotally mounted upon the stud 22 adjacent the said sector 20 and is provided with an opening 28 which registers with and exposes therethrough the markings upon the said sector 20. A spring-pressed member 29 is carried by the arm 27 and is provided in the end thereof with suitable teeth which are adapted to engage the notches 21 of the sector 20. An operating button 30 fixed to the end of the notched member 29 provides a means to draw the said member from its normal engagement with the notches 21 of the sector for the adjustment of the said arm. This adjusting arm 27 is arranged for a relative movement with respect to the said sector 20 and is adapted to be locked in numerous adjusted positions upon the said sector in which positions the number of envelopes to be counted is clearly visible through the opening 28. In the return or counterclockwise movement of the sector 20 under the impulse of spring 26 the arm 27 abuts against a stop 66 fixed to the side wall 3 of the chute and having a suitable bumper 65 to cushion the blow.

A slide 30' is mounted in guides 31 and is arranged for a reciprocating movement therein. A bracket 32 fixed to the slide 30' carries in a pivoted relation the previously referred to actuating pawl 23. This pawl 23 is forced to its raised position shown in Fig. 1 by a compression spring 33 and is held from a further upward movement by a stop 34 as shown. The slide on being reciprocated to the right in the drawing will carry with it the pivoted pawl 23, which pawl when in its raised position will not engage a notch of the sector as its angular end 23' will pass over the tooth as indicated by t. The slide 30' is so disposed with reference to the wheel 20 that the pawl 23 carried thereby engages a notch 21 of the wheel during the latter part of its movement to the right, and the stroke is preferably longer than is required to move the wheel one notch, thereby resulting in a substantial over-travel of the pawl 23.

Suitable electro-magnets 35 are fixed to the slide 30' and are adapted to attract and hold the pawl 23 thereto when energized by an electric current. When the pawl 23 is held in its downward position by the magnets it then will in its forward reciprocating movement engage a notch of the sector 20 and rotate the same one step. A battery B or any other suitable source of electrical current is provided and is connected by a suitable conductor 36 to the contact 15. A conductor 37 connects the said battery to the magnets 35 and a conductor 38 connects the magnets 35 to the contact 13. Thus, an electrical circuit is provided which controls the engagement of the pawl 23 and notches 21 of the counter and said circuit is opened

or closed by the previously referred to contacts 13 and 15.

A bell-crank 40 is pivotally mounted upon the stud 41 and has one end 42 in engagement with a suitable slot 43 of the slide 30' 70 while its other arm is pivotally connected to the reciprocable operating rod 6 previously described whereby the slide is reciprocated by the rocking of the lever 40 in unison with the reciprocation of the plunger 5. 75

A latch 48 is pivotally mounted on the wall 3 of the chute and is provided with a step 48' for engaging the end 25' of the retaining pawl 25 to hold the pawl from engagement with the notches 21 of the counting sector, when the said pawl has been moved from its engagement by the cam 24 of the sector. A depending rod 45 carried by the slide 30' has an offset portion 46 adapted to engage the latch 48 during the 85 latter part of the return movement of the slide and release the latch 48 from its engagement with the pawl 25 to thereby allow the pawl to be moved by the spring 65 into its holding engagement again with the 90 notches of the sector.

The displacing mechanism for segregating the stacks will now be described by reference to Figs. 2, 3 and 4. A horizontal slide bar 50 is carried in a suitable bracket 95 51 and has fixed to the end thereof a displacing plate 52. This plate is adapted to move transversely of the chute by the sliding action of the bar and is so disposed relative to the incoming envelopes as to 100 engage one edge of the envelope and force it laterally of the chute 1. Inclined teeth 53 are provided on one side of the bar 50, and are adapted to be engaged by interfitting teeth 54 of a vertical slide bar 55. A 105 recess 56' is provided in wall 3 of the chute for the reception of the plate 52 whereby a smooth surface is provided for the reception of envelopes.

The vertical slide bar 55 is slidably 110 mounted in the guides 57 and is adapted for a reciprocating movement therein. Teeth 54 are provided in one side of the bar 55 and are disposed at an angle to interfit the teeth 53 of the bar 50. The teeth 53 and teeth 54 are so adapted and arranged that a reciprocating movement of the bar 55 will impart a transverse movement to the bar 50 for the displacing operation. A stop pin 55' fixed to the slide bar 55 as shown, is adapted to abut the under side of the upper guide 57 to limit the upward movement of the said slide bar 55. A tension spring 63 connected to the upper guide 57 and the slide bar 55 functions to return the bar 55 115 to its upper position, and the plate 52 of the horizontal slide bar 50 into its recess after the displacing operation. A roll 56 pivotally mounted upon the said bar is provided 120 and is so disposed as to be engaged by the 125 130

operating mechanism now to be described.

The operating means for the displacing or marking-off mechanism comprises a lever or actuator 60 which is pivotally mounted upon the stud 41 and has its long arm 61 engaging the roll 56 of the vertical slide bar 55 while its short arm 62 is disposed in a position to be engaged by the radial arm 22' of the counting sector 20.

10 In operation, the device may be adjusted to count off any desired predetermined number of envelopes and the number will be segregated by displacing the last one of the desired number as it is delivered to the chute. The displacing of the last envelope of the number as it is delivered to the chute renders it possible to remove from the chute the segregated stack or bunch containing a known or specified number. For illustrative purposes assume it to be required to remove bunches or stacks of ten envelopes. The lever 27 is then adjusted with respect to the sector 20 so that the 10 of the dial is under the opening and registers with the arrow of the lever. During this adjustment the pawl 25 is held by hand or otherwise from engagement with the notches 21 of the sector 20 and the sector 20 carrying with it the lever is allowed to rotate by the action 30 of spring 26 until the lever abuts the bumper 65. With the lever 27 thus set and abutting the bumper the counting mechanism is in condition for the counting operation and in this particular instance will 35 count ten envelopes and the tenth or last of which will be displaced as best shown in Fig. 2.

Since the rod 6 has been connected to reciprocate in unison with the delivery 40 plunger 5, then as each envelope is delivered to the detectors 10 the slide will reciprocate toward the counting sector. As each envelope is delivered to the detectors the contacts 13 and 15 are closed and the electrical 45 current furnished by the battery is conducted to the magnets whereby the pawl 23 is lowered and engages in its forward reciprocating movement successive notches of the counting sector. If, for any reason, the 50 plunger fails to deliver an envelope the detectors will remain in their raised normal position and the contacts 13 and 15 will remain separated, the magnets 35 will not be energized and as a consequence the pawl 55 23 will be held in its upper position by the spring 33 and will not on its forward movement engage a notch of the sector.

So long as successive envelopes are 60 delivered by the plunger 5 the detectors close the circuit upon the delivery of each envelope and the successive notches of the counting sector are engaged by the pawl 23 in its forward movement. The arm 22 of the sector and the cam 24 rotate clockwise 65 and are so disposed with relation to the

notches of the sector, that the last or tenth movement of the said sector brings the arm 22' into abutment with the lever arm 62 by the mechanism described, and causes the displacement of an envelope in the chute. 70 Also, the cam 24 on this last movement engages the pawl 25 and moves it away from the sector, at which time the extension 25' of the pawl is engaged by the shoulder 48' of the latch which holds the said pawl in this inoperative position. The pawl 25 being so locked, the sector is now rotated by action of the spring 26 to its initial position wherein the lever 27 abuts the bumper 65. During the return movement of the slide and after the sector has returned to its initial position the offset portion 46 of the rod 45 abuts the latch 48 and swings it to the left thereby permitting the pawl 25 to be carried by the spring 65 to an operable position where it may again engage the notches of the counting sector. The mechanism is now ready for a repetition of the counting and displacing operation and will 80 continue to act for segregating the envelopes into stacks in the manner described. 85

The lever 27 may be adjusted upon the sector to count any predetermined number of articles and the last one of the number will be displaced with respect to the previously delivered or counted articles in such a manner that the bunch or stack is segregated from the other stacks in the chute. Furthermore, although the slide 30' is 90 operated in unison with the plunger 5 upon the failure of the plunger to deliver an envelope the counting mechanism will not be actuated, thereby insuring that a correct number of envelopes is in each stack before the last envelope is displaced. 100

While I have shown and described the embodiment of my invention as at present preferred, it is obvious that many changes may be made in the device without departing from the scope of the invention. 105

What I claim is—

1. In an envelope stacking mechanism in combination, mechanism for marking off stacks of envelopes, an actuator for said marking-off mechanism, a counting device provided with tripping means for operating said actuator mechanism, said tripping means being adjustable toward and from said actuator for operation upon the counting of various predetermined numbers of envelopes in said stacks, actuating means for said counting device, and an envelope detecting device operable by engagement with an envelope for controlling the operation of said actuating means. 115

2. In an envelope stacking mechanism in combination, means for delivering envelopes in succession thereto, mechanism for marking off stacks of envelopes comprising, a device for displacing one of the envelopes of 120

each stack, a counting device provided with tripping means for operating said marking-off mechanism when a predetermined number of envelopes have been counted, said 5 tripping means comprising a single member adjustable for operation upon the counting of various predetermined numbers of envelopes in said stacks, actuating means for said counting device and an envelope detecting device, operable by engagement with an envelope for controlling the operation of said actuating means.

3. In an envelope stacking mechanism, in combination, means for delivering envelopes 15 in succession thereto, mechanism for marking off of stacks of envelopes, a counting device provided with tripping means for operating said marking-off mechanism when a predetermined number of envelopes have 20 been counted; said tripping means being adjustable for operation upon the counting of various predetermined numbers of envelopes and said counting device comprising a toothed member, and a reciprocating pawl 25 carrier having an actuating pawl mounted thereon for engagement with said toothed member; and an envelope detecting device arranged to engage with the envelopes delivered to said mechanism for controlling 30 the engagement of said actuating pawl with said toothed member.

4. In an envelope stacking mechanism in combination, means for delivering envelopes in succession thereto, mechanism for marking off said stacks comprising a device for displacing one of the envelopes of each stack, a counting device comprising a toothed member adapted to have a step-by-step movement in counting the envelopes delivered to said 40 mechanism, a tripping arm on said toothed member for operating said marking off mechanism when a predetermined number of envelopes have been counted, an adjustable setting arm on said toothed member for determining the number of envelopes to be 45 counted, actuating means for said toothed member, comprising an actuating pawl and a reciprocating pawl carrier therefor, an envelope detecting device comprising a movable feeler located in the path of movement of each delivered envelope, and electro-magnetic means actuated by said feeler for con-

trolling the engagement of said actuating pawl with said toothed member.

5. In an envelope stacking mechanism, in 55 combination, a counting device for counting the number of envelopes to be stacked, actuating means for said counting device, means to reset said counting device to its initial position after being actuated to count a predetermined number, and adjustable setting means for determining the predetermined number to be counted before the resetting of said counting device.

6. In an envelope stacking mechanism, in 65 combination, a counting device for counting the number of envelopes to be stacked, comprising a toothed member, step-by-step actuating means for said counting device, means to reset said toothed member to its 70 initial position after being actuated to count a predetermined number, and a stop arm adjustable on said toothed member for determining the initial position of said toothed member when reset.

7. In an envelope stacking mechanism, in combination, mechanism for marking off stacks of envelopes, a counting device provided with a tripping member for operating said marking-off mechanism, said member 80 being bodily adjustable for operation upon the counting of any predetermined number of envelopes less than the maximum capacity of the counting device, actuating means for said counting device, and an envelope 85 detecting device operable by engagement with an envelope for controlling the operation of said actuating means.

8. In an envelope stacking mechanism, in combination, mechanism for marking off 90 stacks of envelopes, a counting device provided with a pivoted tripping member for operating said marking off mechanism, said member being rotatably adjustable for operation upon the counting of any predetermined number of envelopes up to the maximum capacity of the counting device, actuating means for said counting device, and an envelope detecting device operable by engagement with an envelope for controlling 100 the operation of said actuating means.

In testimony whereof I have affixed my signature.

G. SCHUBACH.

Certificate of Correction.

It is hereby certified that in Letters Patent No. 1,524,213, granted January 27, 1925, upon the application of Gustave Schubach, of Holyoke, Massachusetts, for an improvement in "Stacking Mechanisms," errors appear in the printed specification requiring correction as follows: Page 1, line 94, for the word "same" read *said*; page 2, line 88, for the word "actuated" read *actuating*; page 4, line 117, claim 1, strike out the word "mechanism"; and that the said Letters Patent should be read with these corrections therein that the same may conform to the record of the case in the Patent Office.

Signed and sealed this 3d day of March, A. D. 1925.

[SEAL.]

KARL FENNING,
Acting Commissioner of Patents.
